UNITED STATES PATENT OFFICE.

ABEL FISHER, OF WELLSVILLE, OHIO.

APPARATUS FOR PNEUMATIC PAINTING.

SPECIFICATION forming part of Letters Patent No. 593,013, dated November 2, 1897.

Application filed September 2, 1896. Serial No. 604,624. (No model.)

To all whom it may concern:

Be it known that I, ABEL FISHER, a citizen of the United States, residing in Wellsville, in the county of Columbiana, in the State of Ohio, have invented a certain new and useful Improvement in Apparatus for Pneumatic Painting, of which the following is a true and exact description, the accompanying drawings being had reference to, said drawings forming a part of the specification.

My invention relates to what may be called a "pneumatic painting apparatus," consisting of mechanism designed to facilitate the application of paint to objects to be painted by throwing it upon them in the form of a fine spray.

The object of my invention is to generally improve the construction of apparatus of this kind; and it consists in improvements in the construction of the spraying nozzle or nozzles; also, in improvements in the mechanism which controls the delivery of fluid paint and air to the nozzle; also, in improvements in what may be called the "spraying-head," designed to facilitate its manipulation by the hands of the operator; also, in improvements in the sources of supply of paint and compressed air and in various details of construction.

The nature of my improvements will be best understood as described in connection with the drawings, in which they are illustrated, and in which—

Figure 1 is a side elevation of the spraying-head, taken on the vertical sections 1 1 of Fig. 4. Fig. 1^a is a view of the lower part of the pistol-grip handle. Fig. 2 is an end view of the nozzle; Fig. 3, a sectional view of the nozzle, taken on the section-line 4 4 of Fig. 1. Fig. 4 is a plan view of the spraying-head; Fig. 5, a horizontal section taken on the section-line 2 2 of Fig. 1; Fig. 6, a horizontal section taken on the line 3 3 of Fig. 1. Fig. 7 is a front view of the inner or paint nozzle, showing the construction of its outer walls, which form the inner walls of the air-nozzle. Fig. 8 is a plan view of this nozzle. Fig. 9 is a view taken on section-line 5 5 of Fig. 8, and Fig. 10 is an elevation showing the reservoir-tank combined in operative condition with the spraying-nozzle.

A is the air-nozzle of the spraying device.

It is formed with converging walls A' A', which project, as shown, some distance beyond the end of the paint-nozzle, (indicated at F.) The nozzle A is secured to the tube B in such 55 wise that it can turn upon the tube B for at least an angle of ninety degrees and without loosening the joint between the nozzle and the tube. This may be accomplished in various ways. As shown, I form at the rear of 60 the nozzle A an annular shoulder A², over which fits the flange of threaded tube C, screwing onto the tube B at B', and between the end A³ of the nozzle A and the end of the tube B, I place an elastic washer or gasket 65 D, which will insure a tight joint through a considerable range of movement of the threaded tube or sleeve C.

To supplement the bearing of the end A³ of the nozzle upon the washer D, I prefer to 70 employ a metallic washer E, to which is soldered or otherwise fastened a sleeve E', which passes into the bore of the tube B and forms a wall to prevent the displacement of the elastic washer D.

B³ indicates an annular shoulder at the rear end of the open part of the tube B; B⁴, a threaded perforation; B⁵ B⁶, a tubular extension terminating in a valve-seat B⁶, preferably formed by cutting off the tubular extension B⁵ at an angle which, as shown, is forty-five degrees.

F indicates the paint-spraying nozzle, which is firmly secured to a tube G, said tube G having a threaded end G', which screws into the 85 threaded hole B⁴, and having also an annular flange G², and preferably an annular slot G³ in the rear of said flange. In securing the tube G to the tube B, I prefer to place an elastic washer D' against the annular shoulder 90 B³, and then upon the outside of the elastic washer I place a metallic washer E², against which the flange G² rests when the tube G is screwed down into B⁴. The function of the elastic washer D' is to keep a tight joint, while 95 permitting, as in the case of the elastic washer D, some freedom of motion to the tube G. On each side of the air-nozzle A, I form parallel grooves A⁴, in which fit the lateral edges F⁴ of the nozzle F. The side walls of the 100 nozzle F, like the walls A' of the nozzle A, are of converging shape, and they form the in-

ner walls, so to speak, for the two flat air-jets which issue on each side of the long and narrow paint-jet coming from the nozzle F.

The form of the jets and the convergence 5 of the air-jets above and below the paint-jet, as well as the prolongation of the walls A' beyond the end of the nozzle F, form in part the subject-matter of my pending application for Letters Patent, filed January 7, 1896, Serial 10 No. 574,579. I have, however, improved upon the construction of my said former application by providing a series of diverging or fan-like ribs or fingers F', which are preferably 15 cast upon the outer walls of the nozzle F, as shown, and fit against the walls A' of the nozzle A. These diverging flanges insure the proper spreading out of the air-jets coming from the nozzle A, and have been found an important improvement upon my former construction. To prevent, however, the issuance 20 of the air-jets in separate streams rather than steady sheets, I form at the outer extremity of the ribs F' grooves F², from the outer edges of which the nozzle terminates in plane 25 tongues, as indicated at F³. The function of the grooves is to serve as a reservoir or equalizing chamber for the air, and their presence insures the issuance of the air-jets in flat 30 uniform sheets or bands.

30 It will be noticed that when the nozzles A and F are in operative position they are securely locked together, and when it is desired, for instance, that the jet should be vertical instead of horizontal, as shown, it is only 35 necessary to turn the nozzle A, the motion of which will also turn the nozzle F, the elastic washers D and D' permitting this angular adjustment without liability to leak at the joint. It will be understood that the oil enters 40 the nozzle F through the end B⁶ of the tube B⁵, from which it passes through tube G to the nozzle on the other end. The air enters the tube B through a valve-port B⁸, passing directly to the nozzle A. The port B⁸ connects 45 the tube B with a passage B⁹, which may be conveniently formed in one casting with tube B, as shown, an opening, as indicated at B⁸, being left for the insertion of the valve.

H indicates a metallic ring to which is secured 50 the upper end of the wall J of the paint-reservoir J'. The lower edges of the wall J are secured to a plate I, and the top of the reservoir-chamber is preferably formed of a flexible diaphragm, (indicated at K,) L indicating a metallic cover secured above the diaphragm K and preferably formed into two domes, as indicated at L' and L², L³ being an 55 opening in the covering and L⁴ and L⁵ tubular extensions from the top of the two domes 60 L' and L².

M indicates a paint-supply nozzle entering 65 the reservoir-chamber, which I have marked J', and preferably cut off obliquely, as indicated at M', to form a valve-seat.

65 M² is a flexible paint-supply pipe secured to the tube M by a clamping device—such, for instance, as M³.

The tube M passes through the wall J and has an elastic washer D³ clamped between it and the outside of the wall J, while a metallic washer n is pressed against the inside of the wall by a nut n'.

The tube B is secured to the wall J of the reservoir by means of the tubular extension B⁵, which passes through the walls, an elastic washer D² being placed between the butt-end (indicated at B') of tube B and the wall J, while on the inside of the wall J, I place a washer N, which is pressed against the wall J by the action of a nut N'.

O and o are valve-stems supporting at their lower ends inclined valve-holding devices, as indicated at O' and o'. Flanges O² and o² on the valve-stems rest against the inside of the diaphragm K, while nuts O³ and o³, screwing 85 upon the valve-stems, clamp the diaphragm K against the flanges O² and o². The upper ends of the valve-stems pass into the perforations in spring-adjusting screws O⁴ and o⁴. These screws engage with internal screw-threads in the sleeves L⁴ and L⁵ and adjust the tension of springs O⁵ and o⁵, which rest, respectively, against the nuts O³ and o³.

O⁶ and o⁶ are valve-holding plates by means of which the two obliquely-set valves O⁷ and o⁷ are secured to the valve-spindles and held in position to close the oblique tube-openings B⁶ and M'. By this arrangement and construction of the valves and openings closed thereby I am enabled to use the vertical spindles to advantage, and I will here state that both valves O⁷ and o⁷ are arranged so as to normally close the openings to which they pertain. Thus in the construction shown the springs O⁸ and o⁸, here formed on a single 95 spring-plate, press against the lower ends of the valve-supporting device and press the valves into position against the openings B⁶ and M'. Manipulation of the screws O⁴ and o⁴ regulates the amount of pressure by which the valve is held seated, and obviously the construction described with reference to the valve o⁷, controlling the inflow of paint to the reservoir J', makes this valve in effect a pressure-reducing valve. This is important, as 105 the paint flows through the pipe M at considerable pressure, while only a few pounds pressure is desired in the reservoir J'. The valve O⁷, controlling the delivery of paint from the chamber J', is operated by a pivoted lever P, 110 said lever being pivoted on the cover L at P', having, preferably, a spherical socket P², adapted to rest on the spherical top of the nut O³, while from the outer or free end of the lever extend rods P³ P³, one on each side 115 of the reservoir and each terminating in a thumb-grip P⁴, placed within easy reach of the thumb of the operator, holding the painting device in his hand. I prefer to use two thumb-grips, so that one of them will be within 120 reach of the operator's thumb whether he holds the device in his right or his left hand.

Q is the handle, which is preferably formed, as shown, like the grip or handle of a pistol.

Above the grip proper the handle, which is preferably made in two parts secured together by rivets or screws q , is grooved or slotted, so as to provide a recess to receive the tubular extension B^9 of tube B and its extension and also to give passage to the trigger-valve-controlling device Q^4 , which is pivoted at Q^5 and has an extension Q^6 , which engages the rod R of a valve R' , which controls the air-opening B^8 . The spindle or rod R passes through the stuffing-box, which, as shown, is made up of an annular washer R^2 ; an elastic gasket or washer D^4 , and a perforated screw-block R^3 . The trigger-handle Q^4 lies within reach of the operator's fingers as he grips the handle Q and should preferably lie in a slot or opening Q^8 , so that the fingers gripping the handle Q will normally lie over the trigger Q^4 . A spring Q^7 , which may rest upon a plate Q^8 , screwed to the sides Q' of the handle, serves to hold the valve R' normally in its closed position.

M^2 and S^2 are flexible pipes, one serving as a conduit for paint to the reservoir J' and the other as a conduit for compressed air, leading through the nipple S' and pipe-section S to the pipe extension B^9 already described. These flexible pipes may of course lead from any convenient reservoir or reservoirs, but preferably I connect them with a movable supply-tank for both paint and air, such a tank being shown at T , Fig. 10, the paint-pipe M^2 leading into the bottom of the tank, as shown at U^{10} , V^3 being a valve controlling the flow from the tank at this point. The compressed-air pipe S^2 , I connect with a pipe U^3 , which said pipe opens into the bottom of the tank T at U^4 and into the top of the tank at U^5 , having also at its upper end an opening at U^7 , leading to the open air and controlled by a valve V^2 .

U^2 is a pipe connection leading from the pipe U^3 and preferably having situated in it a pressure-reducing valve, as indicated at U' , U being a removable pipe by which the pipe-section U^2 can be at will connected with an air-pump or reservoir of compressed air—as, for instance, as indicated at W . Valves V and V' are situated in the pipe U^3 below the connection of the pipe S^2 with said pipe U^3 and above the connection of the pipe U^2 with said pipe. U^8 indicates a pressure-gage secured on an elbow U^6 of the pipe U^3 .

T' indicates the cover of the tank, which is pressed down upon the top thereof conveniently by means of a screw T^5 , upon which a hand-wheel T^6 screws. The lower end of the screw T^5 is engaged, through its head T^4 , by a yoke-piece T^2 , and the hand-wheel screws down upon a clamping device T^8 , which rests upon the top T^9 . Most conveniently the tank T is secured to a wheelbarrow-like vehicle Y , having a front wheel Y' , while iron feet Y^2 , secured to the bottom of the tank, take the place of the legs of the wheelbarrow.

In filling the tank the paint is most con-

veniently introduced from the top, being of course in liquid form. Then to charge the tank with compressed air the valve V is closed and the valve V' opened and compressed air is permitted to enter through U^2 , U^3 , and U^5 until the desired amount is contained in the tank. I prefer to charge the tank at a pressure in the neighborhood of sixty pounds per square inch. The tank charged as above, together with the flexible pipes leading from the tank and the handle carrying the spraying device, can be transported readily from place to place, as desired. When in use, the valve V^3 is opened, permitting the paint to flow from the pipe M^2 , while of course the air is permitted to flow through the pipe S^2 . The paint, by the reducing-valve already described, flows into the reservoir J' until at very much reduced pressure, and is not permitted to exceed this pressure in said reservoir.

From time to time it is necessary to stir the paint in the tank, and this is accomplished by closing the valve V' , opening the valve V , and opening the valve V^2 . Then connecting the pipe U^3 with the source of compressed air U the air will flow into the bottom of the tank at U^4 and escape from the top of the tank through U^5 and U^7 , effecting, of course, a complete stirring of the contents of the tank.

Having now described my invention, what I claim as new, and desire to secure by Letters Patent, is—

1. A paint-spraying device having a pistol-grip as Q , valves as O^7 and R' controlling the flow of paint and impelling fluid to the spraying-nozzle and trigger-valve-actuating devices as Q^4 and P^4 one lying in reach of the fingers and the other within reach of the thumb when the grip Q is held in the hand.

2. A paint-spraying device having a pistol-grip as Q , valves as O^7 and R' controlling the flow of paint and impelling fluid to the spraying-nozzle and trigger-valve-actuating devices for opening said valves, one as Q^4 lying in front of grip Q and the others P^4 extending on each side of grip Q to position within easy reach of the thumb of the operator.

3. A paint-spraying nozzle having supported upon a handle as Q a paint-reservoir J' and a narrow diverging paint-conduit as B^9 S and having also nozzle jet-forming devices as A and F in combination with valves as R' and O^7 controlling the flow of air and paint to the nozzle and a pressure-reducing valve as O^7 controlling the flow of paint to the reservoir J' .

4. In a paint-spraying device the combination with a handle and a tube as B secured thereto, of an oil-nozzle as F attached by a screw-union to the rear end of the said tube an elastic gasket D' , against which said screw-union rests, an air-nozzle as A secured by screw-union upon the outer end of tube B and an elastic gasket D , against which said last-mentioned union rests, said nozzles F and

- A being when in operative position locked together as described and so that turning nozzle A will also turn nozzle F.
5. In a paint-spraying device a narrow diverging paint-nozzle as F in combination with narrow diverging nozzles formed on each side thereof, a series of diverging fan-like webs as F' situated in the air-nozzles and serving to spread the jets and an enlargement as F² between the outer ends of the webs and the extreme end of the air-jets.
6. In a paint-spraying device the paint-nozzle F having converging side walls formed with fan-like webs F', grooves F² and smooth ends F³ said nozzle having straight lateral edges F⁴ in combination with the air-nozzle A having converging side walls A' and lateral grooves as A⁴ adapted to receive the lateral edges F⁴ of the paint-nozzle.
7. In a paint-spraying device adapted to be held in the hand and having an oil-reservoir as J' the combination with said reservoir of a paint-delivery pipe as B⁵ having an oblique end B⁶ in the reservoir, an obliquely-set valve O⁷ adapted to close said pipe end and a valve-stem O set substantially at right angles to pipe B⁵ and extending outside of the reservoir.
8. In a paint-spraying device adapted to be held in the hand and having an oil-reservoir as J' the combination with said reservoir of a paint-delivery pipe as B⁵ having an oblique end B⁶ in the reservoir, a paint-receiving pipe as M having also an oblique end M' in the reservoir, obliquely-set valves O⁷ and O⁸ arranged to close the pipe ends B⁶ and M', valve-stems as O and o extending through the walls of the reservoir, a spring or springs as O⁸ o⁸ acting to close valves O⁷ o⁸ and adjustable springs as O⁵ o⁵ acting against springs O⁸ o⁸ as described.
9. In a paint-spraying device substantially as described the paint-reservoir J' having a

flexible top as K in combination with pipes B⁵ and M, valves adapted to close said pipes 45 and valve-stems secured thereto said stems passing through and being clamped to the flexible top K.

10. In a paint-spraying device substantially as described the paint-reservoir J' having a flexible top as K and metallic cover L in combination with pipes B⁵ and M, valves adapted to close said pipes and valve-stems secured thereto said stems passing through and being clamped to the flexible top K, springs as O⁵ o⁵ 55 arranged to press down on the valve-stems and adjusting-screws as O⁴ o⁴ for regulating the tension of said springs.

11. In combination with a hand paint-spraying device having flexible supply-pipes M² and S² a portable reservoir T having a pipe U³ connecting with the reservoir at top and bottom, a receiving connection as U², valves as V and V' situated below and above connection U², an escape-opening as U⁷ situated above valve 65 V', a valve V² controlling the escape-opening, a connection U⁹ for flexible pipe S² situated between valves V and V', and a connection U¹⁰ for pipe M².

12. In combination with a hand paint-spraying device having flexible supply-pipes M² and S², a portable reservoir T having a pipe U³ connecting with the reservoir at top and bottom, a receiving connection as U², a pressure-reducing valve U' situated therein, valves as 75 V and V' situated below and above connection U² an escape-opening as U⁷ situated above valve V' a valve V² controlling the escape-opening, a connection U⁹ for flexible pipe S² situated between valves V and V' and a connection U¹⁰ for pipe M².
